UNITED STATES PATENT OFFICE.

OTTO CARLSON, OF HASTINGS, PENNSYLVANIA.

DESIGN FOR A CAN-OPENER.

SPECIFICATION forming part of Design No. 27,208, dated June 15, 1897.

Application filed April 29, 1897. Serial No. 634,473. Term of patent 7 years.

To all whom it may concern:

Be it known that I, OTTO CARLSON, a citizen of the United States, residing at Hastings, in the county of Cambria and State of Pennsylvania, have invented and produced a certain new and original Design for Can-Openers; and I do declare the following to be a full, clear, and exact description of the invention, such as will enable others skilled in the art to 10 which it appertains to make and use the same.

My invention has relation to a new and original design for can-openers.

It consists of a can-opener of the configuration and ornamentation shown in the accompanying drawings, in which—

Figure 1 is a perspective view of my improved can-opener, and Fig. 2 is a transverse sectional view through the same.

The leading features of my design consist

in the shank 1, provided at one end with a handle 2 and at the other end with a blade 3, which is provided with a rounded back 4 and a cutting edge 5, and above which projects in an inclined direction from the side an arm 6, provided with two prongs 7.

A can-opener thus constructed will be found very useful, and by its employment all liability of the hands being cut or torn is entirely overcome.

What I claim is—

The design for a can-opener, as herein shown and described.

In testimony whereof I hereunto affix my signature in presence of two witnesses.

OTTO CARLSON.
